UNITED STATES PATENT OFFICE.

JOHN EDWARD GOODWIN, OF STOKE-ON-TRENT, ENGLAND, ASSIGNOR TO JOSIAH WEDGWOOD & SONS, INC. OF AMERICA, OF NEW YORK, N. Y., A CORPORATION OF NEW YORK.

DESIGN FOR A PLATE OR SIMILAR ARTICLE.

Application filed July 12, 1924. Serial No. 10,133. Term of patent 14 years.

To all whom it may concern:

Be it known that I, JOHN EDWARD GOODWIN, a subject of Great Britain, residing at No. 13 Wilson Street, Stoke-on-Trent, Staffordshire, England, have invented a new, original, and ornamental Design for a Plate or Similar Article, of which the following is a specification, reference being had to the accompanying drawing, forming part thereof.

Figure 1 is a plan view of a plate showing my new design applied thereto, it being un-

derstood that the border decorations are continued around the entire circumference of the article.

Fig. 2 is a side elevation of a plate with a broken section, showing my new design applied thereto.

I claim—

The ornamental design for a plate or similar article as shown and described.

In testimony whereof I have signed my name to this specification.

JOHN EDWARD GOODWIN.
